UNITED STATES PATENT OFFICE.

PETER DRAIS, OF WASHINGTON COURT-HOUSE, OHIO, ASSIGNOR TO ALMER HEGLER AND ELIJAH HOPKINS, BOTH OF SAME PLACE.

NOSE-RING.

SPECIFICATION forming part of Letters Patent No. 243,064, dated June 21, 1881.

Application filed April 30, 1881. (No model.)

To all whom it may concern:

Be it known that I, PETER DRAIS, of Washington Court-House, in the county of Fayette and State of Ohio, have invented certain new and useful Improvements in Nose-Rings; and I do hereby declare the following to be a full, clear, and exact description of the invention, such as will enable others skilled in the art to which it pertains to make and use it, reference being had to the accompanying drawings, which form part of this specification.

My invention relates to an improvement in nose-rings, the object of the same being to prevent hogs from rooting, and also to enable the animals to be identified by providing an elongated neck to the ring, which serves the double purpose for attaching a tag and also allowing the meeting ends of the ring to be widely separated without breaking the fibers of the metal.

With these ends in view my invention consists in certain details in construction and arrangement of parts, as will be more fully explained, and pointed out in the claim.

In the accompanying drawings, Figure 1 is a view of the ring with its meeting ends open, and Fig. 2 is a view of the same with the ends closed and locked and the tag in position.

A represents the ring, made of any suitable metal, having an eye, *a*, formed thereon at one extremity, into which the opposite end, *b*, which is sharpened or pointed to penetrate the snout, enters. If desired, this sharpened or pointed end may be clinched or turned under the eye, which will effectually hold the ring in position and prevent its being withdrawn if the animal attempts to root when the ring is in position. These rings are constructed by a machine patented to me October 26, 1880, No. 233,606, wherein will be found the manner of making the same.

The elongated neck *B*, or that portion of the ring which receives the tag, is formed by curving the wire and running the same backward a short distance toward the starting-point parallel to the lower portion of the said neck. The wire is then continued upward at right angles to the top of the neck *B* the desired distance, and is then curved over and descends, with the sharp or pointed end passing through the eye.

When the ring is turned out from the machine referred to it is in the position represented in Fig. 1, with the pointed end *b* thrown up and out of engagement with the eye *a*.

To place the ring in the animal's nose, the tag *C* is first placed on the ring, and the ring then placed in the nose-ringer and secured in the usual manner, with the elongated neck and tag sticking outward, which prevents the hog from rooting by providing a leverage which acts with sufficient effect, and also allows the tag to be easily examined to ascertain the owner's name or any memorandum that may be stamped thereon. The elongated neck also allows the ring to be used a number of times without materially weakening the same or breaking the fibers, as is the case with a great majority of the rings now in use, where all the strain caused by the bending comes on a sharp angle, where there is insufficient metal to withstand the strain while being made, and also during its introduction in the hog's nose; but with my improved ring I am enabled to bring the pointed end into the eye when the parts are widely separated without injury to the same. When the ring has been secured in the nose of the hog the tag is prevented from slipping and sliding backward and getting under the hog's snout by bringing the inner faces of the elongated neck in apposition near the inner end of the neck, which retains the ring in position.

Having fully described my invention, what I claim as new, and desire to secure by Letters Patent, is—

As an article of manufacture, a nose-ring bent substantially as shown, having an eye, an elongated neck for attaching a tag, and a sharp or pointed end to enter the eye, substantially as set forth.

In testimony that I claim the foregoing I have hereunto set my hand and seal this 26th day of April, 1881.

PETER DRAIS. [L. S.]
